UNITED STATES PATENT OFFICE

2,614,567

BINDER

Edward C. Kinney, Chicago, Ill.

Application June 21, 1949, Serial No. 100,497

1 Claim. (Cl. 129—36)

1

My invention relates to a binder for holding loose sheets.

Among the objects of my invention is to provide a binder to be quickly and easily applied to loose sheets to hold them together, and which may be as quickly and easily released therefrom; to create a binder formed of cardboard and operated by rubber bands; to present a holder which will firmly hold sheets formed to be inserted therein.

My invention also contemplates such other objects, advantages and capabilities as will later more fully appear and which are inherently possessed by my invention.

While I have shown in the accompanying drawings a preferred embodiment of my invention, yet it is understood that the same is susceptible of modification and change without departing from the spirit of my invention.

Referring to the drawings, Fig. 1 is plan view of my blank and Fig. 2 is an edge view of the same; Fig. 3 is a plan view of my blank with the stiffener attached and Fig. 4 is an edge view of the same; Fig. 5 is an enlarged view of the blank partly broken away and showing the notches; Fig. 6 is an enlarged end view of my binder with the sheets shown in dotted lines; Fig. 7 is an end view of my binder without the sheets; Fig. 8 is a view of my cover and Fig. 9 is an edge view of the same; Fig. 10 is a view of my sheet; Figs. 11 and 12 are edge views of modified structures and Fig. 13 is a view of the blank for the binder shown in Fig. 12.

The embodiment selected to illustrate my invention comprises a blank 10 preferably formed of cardboard with a glazed surface. My blank 10 is rectangular in shape with opposite edges 11 and 12. A longitudinal score 13 extends across blank 10 at a point inwardly from edge 11 forming outer portion 14 and a corresponding longitudinal score 15 extends across blank 10 at a point inwardly an equal distance from edge 12 forming opposite outer portion 16.

Inwardly spaced from score 13 an equal distance is longitudinal score 25 forming intermediate portion 26 and correspondingly inwardly spaced from score 15 is longitudinal score 27 forming opposite intermediate portion 28. Between longitudinal scores 25 and 27 is smaller central portion 29.

Outer portions 14 and 16 may be of greater thickness than the other portions 26, 28 and 29 and may be reinforced or thickened by a filler 22 or any other suitable thickening means.

Outer portions 14 and 16 are respectively bent

inwardly on scores 13 and 15, and upper and lower intermediate portions 26 and 28 are respectively bent inwardly on scores 25 and 27.

Extending longitudinally from both the upper and lower edges of outer portions 14 and 16 are horizontally spaced slots 30 and 31.

10 A resilient loop member 32, preferably a rubber band, is positioned to extend between opposite slots 30 of portions 14 and 16 and another resilient loop member 33, preferably a rubber band, is positioned to extend between opposite slots 31 of portions 14 and 16.

15 The smooth surfaces of portions 14 and 16 are adapted to receive between them inserted side ends of a plurality of sheets 34. The bands 32 and 33 are adapted to stretch to permit the reinforced portions to be moved away from each other for the insertion of the sheets and then to contract by their inherent resiliency for holding the sheets in position.

20 Each of the sheets 34 has extending longitudinally from its upper and lower edges a pair of horizontally spaced slots 35 and 36. Slots 35 are positioned to receive loop 32 and slots 36 receive loop 33. By this construction, sheets 34 are firmly held against accidental disengagement.

25 A front cover 37 has an inner portion 38 of substantially the same width as intermediate portion 26 and is attached thereto by suitable means such as an adhesive. A longitudinal score 39 is at the outer end of inner portion 38. Front cover 37 is bent inwardly on score 39. Extending beyond score 39 is major cover portion 40.

30 A corresponding lower cover 41 has an inner portion 42 of substantially the same width as intermediate portion 28 and is attached thereto by suitable means such as an adhesive. A longitudinal score 43 is at the outer end of inner portion 42. Rear cover 41 is bent inwardly on score 43. Extending beyond score 43 is major cover portion 44.

35 Instead of covers 37 and 41 being attached to the binder, they may be integral therewith, as shown in Fig. 11.

40 It is also within the contemplation of my invention that the number of slots in both my binder and sheet may be varied. For instance, I may provide only one slot in each of the upper and lower edges of my binder and my sheet, or I may provide more than the preferred number of two described herein.

45 It is also within the spirit of my invention to reinforce or not reinforce outer portions 14 and 16. Reinforcement may be obtained by providing a filler or by doubling or further folding on it-

55

self the material to obtain thickened outer portions. Such layers may or may not be attached to each other by adhesives or the like.

As shown in Figs. 12 and 13 my blank and cover may be integral. At the outer end of portion 14 is a longitudinal score 45 and spaced outwardly therefrom is another longitudinal score 46 forming outer end portion 47. Correspondingly at the outer end of portion 16 is a longitudinal score 48 and spaced outwardly therefrom is another longitudinal score 49 forming outer end portion 50. Portion 14 on its upper and lower edges has longitudinal slots 51 spaced horizontally from longitudinal slots 52 on the upper and lower edges of portion 47. When my blank is bent outwardly on score 45 slots 51 and 52 are in alignment. Likewise, portion 16 on its upper and lower edges has longitudinal slots 53, spaced horizontally from slots 54 on the upper and lower edges of portion 48. When my blank is bent outwardly on score 48 slots 53 and 54 are in alignment. A single resilient member 55 extends between said slots. This embodiment of my binder is adapted to hold sheets or cards 34 as shown in Fig. 12. Extending integrally outwardly beyond score 46 is upper cover 56. Extending integrally outwardly beyond score 49 is lower cover 57.

Applicant's co-pending application Serial No. 88,253 has matured into Patent 2,521,296, issued on September 5, 1950.

Having thus described my invention, I claim:

A binder for loose sheets comprising a pair of opposite outer portions, a pair of spaced intermediate portions adjacent and integral with said outer portions, and a central portion between and integral with said intermediate portions, horizontally spaced longitudinally extending scores separating said intermediate portions from said outer portions and from said central portion, the upper and lower edges of each of said outer portions having a pair of horizontally spaced longitudinally extending slots, said outer portions bent inwardly on the scores between them and said

intermediate portions, said intermediate portions bent inwardly on the scores between them and said central portion, so that said outer portions are opposite each other, and a pair of rubber bands extending around said outer portions and positioned within said slots, and contacting the outer surface of said outer portions to move opposite outer portions into contact, said intermediate portions covering said rubber bands, said bands adapted to be stretched to permit said outer portions to part to receive the inner edges of a plurality of loose sheets therebetween and to contract to hold the inserted sheets, and integral front and back covers, each cover having an inner portion adjoining and integral with an outer portion of the binder and a major portion integral with an inner portion of the cover, a longitudinal score between each inner portion of the cover and adjoining outer portion of the binder, each cover bent inwardly on said score so that said inner portion of the cover extends along and is coextensive with said outer portion of the binder, and a longitudinal score between each inner and major portions of the cover, each cover bent outwardly on said score and extending horizontally beyond the binder and of sufficient size to cover the inserted sheets.

EDWARD C. KINNEY.
